PRINTING TELEGRAPH APPARATUS.

Howard L. Krum, Kenilworth, Ill., assignor to
Teletype Corporation, Chicago, Ill., a corpora-
tion of Delaware

Application May 6, 1937, Serial No. 141,042

28 Claims. (Cl. 178—27)

This invention pertains to printing telegraph apparatus and especially to a type wheel printer for recording characters in page form.

The primary object of the invention is to provide a lightweight and readily portable page printer which is reliable and efficient in operation.

Another object is to provide a type wheel printer in which the chief operating characteristics are analogous to those inherent in certain extensively employed type bar printers, to render the former printers capable of operation in the same telegraph circuits with the latter printers for recording the same message line for line and perform the same functions.

Briefly, the apparatus according to the present invention employs a single magnet permutation code selector, the selections on which are transferred to a series of code bars, which selectively control a plurality of selectable stop levers, which in turn cooperate with a corresponding plurality of stop arms helically arranged around and affixed to a rotatable cylindrical member. Each of the stop arms terminates in two steps or shoulders, so that each arm governs the positionment of two characters on a type wheel. The type wheel consists of a circular disc, having equally spaced radial slots, thus forming a series of radiating reeds, upon which the letters and figures are arranged in a single row. The upper and lower case characters are arranged alternately and mechanism is provided for shifting the type wheel angularly, or rotationally, relative to the axis of the supporting shaft, one-half step, the distance between two successive characters in the same case being considered as one step.

A cylindrical platen is movable to effect character spacing, is rotated for line feeding, and is further controlled by character spacing and carriage return mechanisms. Visible printing is attained by withdrawing the type wheel from the platen, after printing, a substantial distance sufficient to preclude obstruction of vision. The usual functions of suppressing spacing and printing during the performance of certain other functions (for example, case shift, carriage return, and line feed) are included.

The keyboard has been designed with a view toward providing a compact organization of parts. To achieve this result the key levers have a concave depression, into the hollow of which is positioned the motor. By permitting the motor to be thus lowered, the height of the apparatus is reduced appreciably.

The functions are performed by levers actuated

from cams on the vertically disposed main shaft, after being conditioned for operation by drop bars in the selector mechanism. Ink is supplied to the character faces on the type wheel by means of an inking roller to simplify the construction, but it is, of course, understood that ribbon feed and reversing mechanisms can readily be applied. In connection with the carriage return mechanism, spacing and retaining pawls, when withdrawn from engagement with the spacing rack, are latched into drawn position and remain latched until the carriage return operation is completed and the next character is printed, whereupon they are unlatched and are permitted to again engage the spacing rack, thus insuring a uniform margin for printed lines.

The foregoing and other objects of the invention will be apparent from the following description when taken in conjunction with the accompanying drawings, wherein like reference characters designate similar parts throughout the several views, and in which

Fig. 1 is a perspective view of the combined transmitting and receiving apparatus in accordance with the invention;

Fig. 2 is a perspective view of a part of the selector mechanism;

Fig. 3 is a side elevational view of the combined transmitting and receiving apparatus according to the present invention;

Fig. 4 is a top view of the receiving apparatus;

Fig. 5 is a cross-sectional view of the combined transmitting and receiving apparatus;

Fig. 6 is a sectional plan view, with parts broken away, to illustrate various internal mechanisms of the receiving apparatus;

Fig. 7 is a front elevational view, with parts broken away, of the combined apparatus according to the present invention;

Fig. 8 is an end view of the type wheel shaft 40 with the type wheel broken away to show the relative positions of the star wheel and stop arms;

Fig. 9 is a cross-sectional detail of the code bar and selector member arrangement;

Fig. 10 is a fragmental cross-sectional view of the taut wire paper tearing edge; and

Fig. 11 is a modified form of selector mechanism.

The combination sending-receiving apparatus comprises essentially a printing unit indicated generally by the numeral 11, and a keyboard transmitting apparatus indicated generally by the numeral 12. In practice, two or more of such apparatuses are interconnected in a telegraphic signal line for intercommunication. Al- 55

though various forms of transmitting mechanisms may be employed, the one chosen to illustrate the present embodiment is in accordance with the transmitter mechanism disclosed in United States Patent No. 1,595,472. As shown in Figs. 1, 3, 5, and 7, the keyboard 12 is provided with a set of keys 13 arranged similarly to the well-known typewriter keyboard, and as illustrated in Fig. 5, key levers 14 associated with the keys 13 are pivotally mounted on a common shaft 15 and are spring held in normal horizontal position by individual springs 16. Arranged transversely below the key levers 14 in operative relation thereto are a series of five V-notched selector bars 17 (Fig. 7) operated permutably, in a well-known manner, in accordance with the key depressed.

The selector bars 17 have pivotally articulated thereto a corresponding series of locking latches 18 (Fig. 7) rocked thereby to either of two positions. Associated with latches 18 are a corresponding series of contact levers 19 for making and breaking contacts 20 (Fig. 3). Contact levers 19 cooperate with individual contact cams 21 mounted on the transmitting shaft 22 (Fig. 7) which is provided with a clutch mechanism 30 controlled by a trip member 40 connected to a universal bar member as set forth in United States Patent No. 1,965,602.

In the operation of the transmitting unit, the depression of a key lever 14 moves the selector bars 17 permutably in accordance with a predetermined code combination, the setting of which determines the positions of the locking latches 18. The rotation of the cams 21 is initiated substantially simultaneously with the setting of the locking latches, through the instrumentality of strip member 40, and the locking loop 23 controlled by a cam 50 (Fig. 3) carried on the shaft 22 is permitted to rotate in a counterclockwise direction (Fig. 7) to lock the latches 18 in their selected positions. The setting of latches 18 determines whether the contact levers 19 shall or shall not be affected by their associated cams 21 to cause the opening or closing of their associated contacts 20 to transmit over a signal line, to the receiving station, a predetermined code combination of signaling impulses. The respective notches in the cams 21 are arranged in a helical progression so that upon the rotation of the cam assembly, the contacts controlled by levers 19 will be operated successively. The apparatus herein disclosed is operated in accordance with an equal length letter code, in which each code combination is a permutation of marking and spacing conditions, and is preceded by a start impulse and followed by a stop impulse, according to the familiar start-stop system.

Power is transmitted to the transmitting shaft 22 from an electric motor 25 through a pinion gear 60 (carried on the motor shaft 24) and spiral gear 70 fixed to shaft 22. As previously mentioned, the motor 25 is arranged to be supported in a hollow or concave portion 26, to compensate for which the key levers 14 have been shaped correspondingly to follow the contour of the portion 26, Fig. 1.

A pinion gear 27 is fixed to the motor drive shaft 24 and meshes with a gear 28 carried on a vertically disposed main shaft 29 (Fig. 5). Shaft 29 has affixed thereto a collared member 31 (Fig. 3) and is supported therethrough by a supporting bracket 32. The shaft depends therefrom and is guided at its lower end by a bracket 33. Carried on shaft 29 is a sleeve member 34

(Fig. 5) on which are carried, as also indicated in Fig. 3, a spacing cam 35, a transfer cam 36, and a printing cam 37. The functional mechanisms associated with these cams will be described hereinafter.

A toothed or grab clutch, indicated generally as 38, is carried on shaft 29, and is superposed above sleeve 34 (Fig. 5) and comprises a driving portion 39 (Fig. 3) fixed to the shaft 29 and a driven portion 41 articulated by a tongue and groove connection 42 to the sleeve member 34. Driven portion 41 of the clutch 38 is normally urged upwardly by a coil spring 43, which movement is resisted by arm 44 of a release bail 45 pivotally carried on a bracket 46 affixed to the printer frame 47. Arm 44 cooperates with a cam portion 48 integral with the driven portion 41 of the clutch 38. As the release bail is rocked in a manner presently described, the arm 44 thereof will be actuated outwardly (counterclockwise as viewed in Fig. 1) out of engagement with cam portion 48, whereupon spring 43 will urge the driven portion 41 of clutch 38 upwardly into mesh with the driving portion 39 which is constantly rotating. Then, after a single revolution has been completed, arm 44, which has been returned into its position against the clutch portion 41 by a spring 49 (Fig. 1), the coaction between arm 44 and the cam portion 48 will cause the camming-out or disengagement of portion 41 from portion 39. Clutch 38 is referred to as a single revolution clutch. Shaft 29 extends above bearing 32 and carries thereon a selector cam drum 51 and related elements. However, disposed between the cam drum 51 and the bracket 32 and affixed to shaft 29 is a gear 52 which meshes with a gear 53 (Figs. 1 and 5) frictionally carried on an auxiliary shaft 54.

Fixed to the upper end of shaft 29 is a disc 55 (Fig. 3). Cam drum 51 is frictionally driven by shaft 29 through the instrumentality of friction discs 56 and 57. Friction disc 56 is compressed between disc 55 and flange 58 of cam drum 51, and friction disc 57 is compressed between flange 58 of cam drum 51 and a disc 61 by a helical spring 62. By this means, cam drum 51 will rotate with shaft 29 except when it is arrested by the engagement of stop lug 63 integral with cam drum 51 and a stop gate 64.

Stop gate 64 is mounted on a pivot stud 65 secured to an adjustable plate 66 (Figs. 3 and 4) and its upper arm 67 is adapted to be engaged by a latch 68. The latch 68 is pivoted in a journal block 69, and this journal block is in turn mounted on the adjusting plate 66. Plate 66 may be rotated about a pivot stud 71 by means of an orientation control device indicated generally by the numeral 72 (Fig. 4) and as described in Patent No. 2,082,511 granted June 1, 1937. As shown in Fig. 3, both the latch 68 and the stop gate 64 are carried on the adjusting plate 66 and are movable therewith. By means of this orientation adjustment, the position of arm 73 of stop gate 64 may be altered to obtain the best operating conditions of the selector, as described in Patent No. 2,082,511. Associated with latch 68 is a bell crank lever 74 (Fig. 3) pivotally carried in a journal block 75 mounted on plate 76 of the orientation device. Associated with the vertical arm of bell crank 74 and carried in block 75 is a plunger 77 which, as shown in Fig. 4, cooperates with arm 78 of a selector lever 79. Latch 68 is normally biased in a clockwise direction (as viewed in Fig. 3) 75

by a coil spring 81 so that it is normally brought into locking relation with arm 67 of stop gate 64 and simultaneously therewith bell crank 74 is maintained in its counterclockwise position 5 and plunger 77 in its retracted position. Thus when plunger 77 is depressed or urged rightwardly, as viewed in Fig. 3, by the action of selector lever 79, Fig. 4, as will presently appear, bell crank 74 will be rocked clockwise and latch 10 68 will be rocked counterclockwise against the action of its spring 81 to effect the release of the selector cam drum 51 for rotation, which is effected by the pressure of stop lug 63 against arm 73 of the stop gate 64, which pressure, owing to 15 the release of latch 68 from arm 67, will cause the stop gate 64 to be rotated against the action of its spring 82. When lug 63, in its rotation, escapes arm 73 or stop gate 64, the stop gate will be returned to its locked position in engagement 20 with latch 68 by the action of spring 82, so that when lug 63 again reaches arm 73, it will be arrested thereby due to the detention of arm 67 by latch 68.

Having reference now to Fig. 4, the details 25 of the selector mechanism actuated by the cam drum 51 will be described. The selector cam drum 51 is rotated at a speed substantially the same as the speed of code impulsion, and operating in conjunction therewith is a selector magnet 83 which may be connected either directly or indirectly (through a line relay, for example) to the signal line. Selector magnet 83 is carried on a bracket 84 affixed to the printer frame, and associated with the selector magnet 83 is the 30 selector lever 79 pivoted at 85. Selector lever 79 has a pole piece 86 which cooperates with the core 87 of the selector magnet 83, and is biased, upon deenergization of magnet 83, in a clockwise direction by a spring 88 distended between 35 the pole piece 86 and a spring anchor arm 89. Upon energization of selector magnet 83 by the impression of marking current on the signal line, pole piece 86 will be attracted, causing selector lever 79 to be actuated in a counterclockwise direction against the tension of spring 88.

Selector lever 79 terminates in a T-shaped portion 91 having downwardly extending arms 92 (Fig. 3) which constitute abutments which 40 cooperate with arms 93 on the right ends (Fig. 4) of a series of selector fingers 94. Selector fingers 94 comprise a series of thin, flat members arranged in superposed relation between guide plates 95, and are equal in number to the 45 signaling elements of the code on which the receiving printer operates. Thus, if a five-unit code is employed, there will be five of the selector fingers 94, whereas a six-unit code will require six selector fingers. The guide plates 95 are mounted on studs 96 secured to the selector 50 mounting plate 97 (Fig. 3), and are spaced by washers (not shown). The circular right ends 98 of selector fingers 94 engage corresponding sockets of thin flat bell crank levers 99 pivoted on a common shaft 101. Individual springs 102 bias the bell cranks 99 in their clockwise direction whereby the selector fingers 94 are urged 55 leftwardly (Fig. 4). The pointed ends 103 of bell crank levers 99 are thus maintained in contact with the selector cam drum 51.

Selector cam drum 51 is provided with a helically arranged series of cam projections 55 (Figs. 1 and 3), one for each of the bell cranks 99, which function to rotate the bell cranks 99 in succession and thus draw the selector fingers 94 60 rightwardly (Fig. 4) successively as the selector

cam drum 51 is rotated. In addition to the longitudinal movement, the selector fingers 94 have a laterally swinging movement between a pair of studs 104. The setting of any selector finger 94 either to its clockwise or counterclockwise position is determined by the selector magnet 83; that is, each selector finger 94 is shifted clockwise or counterclockwise by having one or the other of its arms 93 drawn against one or the other of the abutments 92 of the T-shaped portion 91 of selector lever 79. As the signal impulses are received over the telegraph line, the selector magnet 83 is energized and deenergized depending upon the nature of such impulses, and as a result thereof, the abutments 15 92 are caused to cooperate with one or the other of the arms 93 to provide a fulcrum about which the respective selector fingers 94 are rotated.

Since in start-stop systems the normal stop condition of the line is marking or current on 20 the line, the selector magnet 83 will be normally energized and the selector lever 79 will be attracted and held in its counterclockwise position. Upon the receipt of a start impulse, which is of spacing nature, the selector magnet 83 will 25 become deenergized and the spring 88 will bias selector lever 79 in a clockwise direction causing arm 78 to depress plunger 77 to release latch 68 from stop gate 64, thus permitting the selector cam drum 51, through the release of its lug 63, 30 to rotate, which rotation ensues during the reception of a series of impulses constituting a signal. During the rotation of selector cam drum 51, the cam projections 55 successively cooperate with bell crank levers 99 causing them to rotate against 35 the action of their spring 102 to bring the selector fingers 94 rightwardly toward the U-shaped portion 91 of selector lever 79. At the instant of reception of each code impulse, a cam projection 55 coacts with a bell crank 99 so that depending 40 upon whether the code impulse is of marking or spacing nature, the selector lever 79 will assume either its clockwise or counterclockwise position to permit the abutment of one or the other of the arms 93 on selector finger 94 with the corresponding 45 depending arm 92 on selector lever 79. Thus, upon the reception of a marking impulse, selector lever 79 will assume its counterclockwise position to cause the rocking of selector finger 94 to its clockwise position. On the other hand, 50 if the received impulse is of spacing nature, selector magnet 83 will become deenergized and selector lever 79 assumes its clockwise position whereupon selector finger 94 is caused to rock to its counterclockwise position or the position 55 shown in Fig. 4.

The left end of each of the selector fingers 94 cooperates with a T-lever 105 pivoted on a common shaft 106 and are likewise arranged between guide plates 95. The reciprocation longitudinally 60 of fingers 94 by bell cranks 99 under the influence of springs 102 will effect the rocking of T-levers 105 to their clockwise or counterclockwise position depending upon whether fingers 94 are in their counterclockwise or clockwise position, 65 respectively. T-levers 105 are pivotally articulated to individual code bars 115, 120, and 121 (Figs. 7 and 9) of a series of code bars 107 slidably mounted on studs 108 and 109 (Fig. 4). The series of code bars 107 are set permutably 70 in accordance with the received code combinations of impulses by the selector mechanism just described, and are retained in their set position by the coaction of detent member 111 with detent notches 112.

Cooperating with the series of code bars 107 are a plurality of selector drop bars, or abutment members 113 (Fig. 2). In the present embodiment there are eight members 113, and associated with each member 113 is a companion abutment member 114. The ends 119 of arms 116 of selector members 113 and 114 provide abutments for a series of stop arms or projections 100 and 122 helically arranged around and affixed to a cylinder 125 (Figs. 5 and 8). Incidentally, each of the arms 116 has a vertically extending guide lug 117 which cooperates with a guide comb 118 (Figs. 4 and 5). Stop arms 100 and 122 terminate in a pair of stepped shoulders 230 and 124 (Figs. 7 and 8), one or the other of which strikes a selected member 113 or 114, as will presently appear. Although the series of code bars 107 effect the selection of the selector members 113 and/or 114, three of the code bars 115 (Fig. 9), when operated permutably, effect the selection of one of the eight members 113. The bottom code bar 120 of the series of code bars 107 is so arranged with its notches as to permit or prevent the selection of the companion selector member 114. The fifth or top code bar 121 has its wards or projections only about one-half as high as the wards of the code bars 115 so that, compared with code bars 115, code bar 121 may in effect be deemed to have notches of two different depths, one depth functioning to permit a predetermined entrance of the selector member 113 therein to coact with the stop arms 100 or 122 in a certain manner, and the deeper notches permitting a further movement of the selector bars 113 to cause their coaction with the stop arms in a different manner. As shown in Fig. 9, the selector members 113 cooperate only with the upper four code bars 115 and 121, and the companion selector member 114 cooperates only with the bottom code bar 120. Although the abutment members 113 and 114 present the appearance in Fig. 4 of being exactly alike and that the top edges of all said bars are at the same level, a difference does exist, as shown in Figs. 2, 7, and 9, in that the top edges of bars 114 are at a lower level than the top edges of bars 113. For example, referring to Fig. 4, abutment members 113 engage the top code bar 121 and members 114 do not engage the code bar 121, but only the bottom code bar 120 (see Figs. 2 and 9). In the position of code bar 121, as shown in Fig. 4, the third and fourth abutment members 113 (reading from the bottom of the figure) are blocked by code bar 121, while with the alternative position of code bar 121, the first, second, fifth, sixth, seventh, and eighth abutment member 113 would be blocked. Each selector member 113 has a laterally disposed pin or stud 130 (Fig. 7) positioned in the path of rotation of the companion member 114, so that each selector member 113 can, under certain operating conditions, exercise control over its companion member 114, as will be discussed presently.

Selector members 113 and 114 are normally biased in a clockwise direction by springs individual thereto, Figs. 2 and 7. Thus, when the middle three code bars 115 are positioned in accordance with their corresponding code impulses of the code signal, an alignment of notches results to effect the selection of one of the selector members 113. The amount of its clockwise rotation in response to the pull of its spring is determined by the selective position of the top code bar 121; for example, the surface 110 (Fig. 4) of one of the truncated wards of code bar 121 (Fig. 9) will permit the selector member 113 to rotate only to

such an extent that its end 119 is presented into the path of the shoulder 230 of a stop arm 100 or 122. If the top code bar 121 is shifted so as to permit the movement of selector member 113 against the bottom 123 of a deep notch, further rotation is permitted to selector member 113 so that its end 119 is presented into the path of shoulder 124 of its associated stop arm 100 or 122.

With the permutations of the three middle code bars 115, eight selections are possible. With the addition of the top code bar 121, the number of selections is doubled, thereby permitting, with selector members 113, sixteen possible selections. Now, with the further addition of the bottom code bar 120 and the response thereto of selector members 114, the number of selections is increased or again doubled, giving thirty-two possible selections in the following manner: When the bottom code bar 120 is in one of its longitudinal or selective positions, its lugs thereon act to block the clockwise movement of selector member 114, but when the bottom code bar 120 is moved to its alternate position, a notch is presented to the vertical arm of the selector member 114 whereby, when the main selector member 113 is selected and permitted to rotate clockwise under the action of its spring 116, the selector member 114 associated with said selected member 113 is permitted to follow, in which case the actuated member 114 is held against the laterally disposed stud 130 by its spring, and in this manner the main selector member 113 and its companion member 114 move as a unit.

The shoulders 230 and 124 on each of the helically arranged arms 100 and 122 are so positioned angularly (Fig. 8) as to correspond with the angular positions of type faces on a type wheel 128 so that when one of the selector members 113 and 114 is moved into one of the paths of rotation of shoulders 230 and/or 124, the cylinder 125 will be permitted to rotate in a counterclockwise direction until one of the stop arms 100 or 122 is arrested by the selected member 113 or 114. In this manner a character on the type wheel is brought into printing position.

Referring to Figs. 5 and 7, the cylinder 125 which carries the stop arms 100 and 122, is rotatably mounted on shaft 54 at the left end of which (as viewed in Fig. 5) is carried the type wheel 126. The left end of the shaft 54 is counterbored to receive a stub shaft 128 integral with the type wheel assembly and is provided with an open ended slot 129, which engages a pin 131 integral with shaft 128. Shaft 54 is journaled in a bushing 132 carried in a bracket 133 on the printer frame. Shaft 54 is also similarly journaled in bracket 134. A constant torque is applied to shaft 54 through friction means 135 associated with a constantly rotating gear 53, which meshes with gear 52 affixed to the vertical main shaft 29. The frictional connection between gear 53 and shaft 54 is maintained by a coiled compression spring 138.

Rotation is imparted to cylinder 125 by the shaft 54 through the instrumentality of a driving disc 139 affixed to shaft 54. Disc 139 has a laterally disposed arm 141 which, through an interponent 142, coacts with an arm 143 integral with cylinder 125. Thus, when cylinder 125 is free to rotate by the removal of selector members 113 and 114 from the paths of stop arms 122, rotational movement will be imparted thereto by the shaft 54. Arms 141 and 143 are normally biased attrahently by a spring 140 coiled about shaft 54. Interponent 142 is integral with

a sleeve 245 slidably and rotatably carried on shaft 54, which will be further discussed in connection with the shift and unshift functions.

As previously described, there is mounted on the main shaft 29 (Fig. 5) a sleeve 34 which carries, among other cams, a transfer cam 36, which cooperates with a follower roller 136 (Figs. 6 and 7) carried at the extremity of a transfer lever 144 (Figs. 1, 6, and 7) pivotally mounted on a vertical shaft 145. The forward end of transfer lever 144 is pivoted to one end of a link 146 (Fig. 1), the other end of which is pivoted to a depending arm 147 of a transfer bail 148. Transfer bail 148 is rockably carried on a shaft 149 and is provided with a web portion 151 positioned beneath and spanning all of the selector members 113 and 114.

Upon the reception of a code signal, a start impulse thereof acts to initiate the rotation of the selector cam drum 51 to effect the selective positionment of the selector fingers 94 as previously described. However, due to the locking action of the detent 111 upon the code bars 107 (Fig. 4), springs 102 of the selector levers 99 are unable to effect, through T-levers 105 (until at a predetermined instant), the shifting of the code bars 107 to a succeeding selection. Hence, through the instrumentality of the transfer mechanism, this transfer of the setting of the selector fingers 94 to the code bars 107 is accomplished. Therefore, at a predetermined instant in the cycle of rotation of cam drum 51, a cam projection 190 thereon acts upon an arm 152 of clutch release bail 45 to effect the disengagement of arm 44 from cam 48 of the driven portion 41 (Fig. 3) of clutch 38, thus permitting the engagement of portions 41 and 39 of the grab clutch 38 to effect the rotation of cams 35, 36, and 37, of which cam 36 acts to effect the transfer operation.

Upon rotation of cam 36, rotation is imparted to lever 144, which through link 146 (Fig. 1) rocks the transfer bail 148 in a counterclockwise direction which, through its web portion 151, rocks all of the selector members 113 and 114 counterclockwise bringing the vertical arms thereof out of engagement with code bars 107. Simultaneously, detent 111 being controlled by the transfer bail 148 is lifted out of locking engagement with the code bars 107, whereupon code bars 107 are free to be reshifted to their newly selected position in response to the selective positionment of the several selector fingers 94. After permitting sufficient time to effect the shifting of the code bars 107 into their new position, cam 36 permits the transfer bail 148 to be rocked to its clockwise position thus allowing selector members 113 and 114 to be free to respond to the pull of their respective springs 160 and 170 into engagement with the series of code bars 107, as a result of which one of the selector members 113 will find an alignment of notches, whereupon the selected member 113 will rotate clockwise a greater distance into the path of its associated stop arm 100 or 122. A member 113 is invariably selected, the selection of its companion member 114 being effected simultaneously with a member 113 only when it is permitted to do so by the proper positioning of code bar 120. That is, when it is desired to select a member 113 only, its companion member 114 is blocked against rotation under the action of its spring 170 by the code bar 120, and the pin 130 carried by member 113 will be moved free of the companion member 114. On the other hand, when

it is desired to select a member 114, the alignment of notches for its main member 113 is made, and also, code bar 120 is shifted out of blocking engagement with member 114, and hence member 114 is permitted to bear against the pin 130 5 on its companion main member 113 and follow said main member, thus effecting the simultaneous selection of a pair of selector members 113 and 114.

Affixed to the cylinder 125 is a star wheel 153, 10 the teeth or points of which have a definite relation, as will presently appear, with the stop arms 100 and 122, and hence the angular positions of the type faces upon the type wheel 126. Cooperating with the teeth on the star wheel 15 153 is an intercepting arm 154 of a lever 155 (Fig. 1) which is pivotally carried on shaft 149. Lever 155 is provided with a depending arm which coacts with an eccentric adjusting screw 156 mounted on arm 147 of transfer bail 148. 20 A spring 157 distended between an extension on link 146 and a lug integral with lever 155 tends to cause said depending arm to bear constantly against the adjusting screw 156 and to cause lever 155 and transfer bail 148 to rotate as a 25 unit. Thus, when transfer bail 148 is effective during the performance of the transfer operation, as previously described, to rock selector members 113 and 114 out of the path of stop arms 100 and 122, the cylinder 125 will not rotate or spin freely because of the fact that intercepting arm 154 has been biased by spring 157 into the path of the oncoming tooth of the star wheel 153. Then when the transfer bail 148 is returned to its unoperated position, intercepting arm 154 is withdrawn from engagement with the tooth on the star wheel 153 whereupon star wheel 153 and the cylinder 125 are free to rotate until one of the stop arms 100 or 122 is arrested by the impingement of one of the 30 shoulders 230 or 124 thereon against the end 119 of the selected member 113 or 114 to thus bring a type face on the type wheel 126 into printing position.

Printing cam 37 (Figs. 1 and 3) cooperates with 45 a follower roller 158 carried on one arm of a printing control lever 159 pivotally mounted on the vertical shaft 145. The lever 159, as shown in Fig. 6, is normally biased in a counterclockwise direction by a spring 301 sufficient in tension to overcome the tension of printing spring 165 to be described. Lever 159 is articulated to link 161 by a shoulder screw 300 which by opposing tensions of springs 301 and 165 is retained in the forked end of a link 161, the other end of 50 which is pivoted to a printing arm 162 pivotally mounted at 163 upon a bracket 164 integral with the printer frame 47 (Fig. 5). Distended between printing arm 162 and frame 47 is a printing spring 165. Printing arm 162 terminates at 60 its upper end with a striking surface 166 which acts upon the type wheel 126 to effect printing.

The type wheel 126 consists of a circular disc, having cut around the circumference thereof equally spaced radial slots 167 (Fig. 8) thus 65 forming a series of radiating reeds 168 upon which letters and figures are arranged in a single row. Adjacent the striking surface 166 is a V-shaped knife edge 150, which, as printing is being effected, projects into a notch in a peripherally notched corrector disc 180, to properly align and hold the type wheel in printing position in well-known manner. Printing arm 162 is provided, between the link 161 and the end 166, with a hook portion 169 which engages a flange 171 70 75

associated with type wheel 126. In this manner, printing arm 162 is positively actuated by printing lever 159 to impart axial movement to type wheel 126 both before and after printing; the purpose of which is to permit visibility of a printed character. To achieve this result, type wheel 126 is withdrawn from the printing platen 172 a substantial distance by means of the inter-engagement of hook 169 and flange 171.

10 To effect operation of printing arm 162, the printing cam 37 driven by clutch 38 passes its high portion under roller 158 whereby clockwise rotation is imparted to printing lever 159 and shoulder screw 300 is moved toward the end of the slot in link 161, releasing link 161 and printing arm 162 to permit printing by the printing spring 165. However, the first portion of the movement of printing arm 162 is employed, through the instrumentality of hook 169 and flange 171, to bring the type wheel within printing range of the platen 172, whereafter the further movement of printing arm 162 by spring 165 is utilized to present the end 166 thereof against a reed 168 of the type wheel 126, thus bringing the type face thereon against the record material disposed in front of the platen 172. Cam 37 thereafter permits the printing lever 159 to rotate counterclockwise, to effect leftward movement to link 161 to bring printing arm 162 to its counterclockwise position and stretching spring 165 thereby storing energy therein. At the same time, through hook 169 and flange 171, type wheel 126 is withdrawn from the platen to permit visibility of the character last printed. To permit proper adjustment between printing arm 162 and link 161, printing arm 162 is provided with an enlarged hole to receive the shouldered clamping nut 173, and to facilitate this means of adjustment, link 161 is provided with an open ended slot 174 adapted to engage a guide pin 175 mounted on printing arm 162.

15 Platen 172 is carried in a carriage or frame indicated generally by the numeral 176 (Figs. 4 and 5). Associated with platen 172 are pressure and guide rollers 177 which are of well-known construction and are not a part of the present invention. The platen carriage 176 is slidably mounted upon the frame 41 of the printer through the medium of ball bearings 178 and 179.

20 Mounted on the platen carriage 176 is a spacing rack 181 (Figs. 6 and 7), and cooperating with rack 181 is a spacing pawl 182 pivotally mounted on an arm 183 of a plural arm lever 184. Pawl 182 is normally biased into engagement with rack 181 by a spring 187. Arm 185 of lever 184 carries a follower roller 186 which cooperates with the spacing cam 35 previously mentioned. Thus upon rotation of cam 35, when arm 44 is disengaged from the driven clutch member 41, clockwise rotation is imparted to lever 184 causing pawl 182 to be actuated leftwardly, as viewed in Fig. 6, to move rack 181 one tooth and to move thereby the platen carriage 176 one character space. To retain the platen carriage at the character space position to which it has been just moved, a detent pawl 188 is provided which also cooperates with rack 181 and is spring biased thereagainst by a spring 189. As the platen carriage is actuated leftwardly, as viewed in Figs. 4, 6, and 7, it tends to wind up a carriage return spring enclosed in a spring housing 191 (Fig. 4), thus storing up energy to effect, upon receipt of the carriage return signal, the carriage return operation, the carriage return spring being con-

nected to the platen carriage in well-known manner.

Certain of the companion members 114 control the function operations, such as carriage return, line feed, shift and unshift, and have depending arms 192, 212, 227, and 228, respectively (Figs. 1, 2, and 7), which control the suppression of the printing and spacing operations. As a function selector member 114 is rocked clockwise by its spring 170, its depending arm 192, 212, 227 or 228 acts on a bail portion 193 of a printing and spacing cut-out lever 194 (Figs. 1 and 7) to cause said lever 194 to be rocked clockwise. Lever 194 is normally biased in a counterclockwise direction by a spring 202.

25 Lever 194 has an arm 195 which extends in front of and blocks, under certain operating conditions, a projection 196 (Figs. 1 and 5) integral with link 161, thus during the operation of a function wherein it is desired to prevent the printing and spacing operations, arm 195 is presented into the path of lug 196 so that when the printing spring 165 tends to operate the printing arm 162, it is prevented from so doing by the blocking action of lever arm 195 upon link 161, thus cutting out the printing operation when certain functions are performed. Simultaneously therewith, character spacing of the platen carriage 176 is prevented in the following manner: Lever 194 is also provided with a curved arm 197 (Fig. 2) to the terminal end of which is pivoted one end of a link 198, the other end of which is pivotally articulated to one arm of a bell crank lever 199 (Fig. 6) pivotally mounted on the printer frame 41. The other arm of bell crank 30 199 carries a stud 201 engaging a slot in pawl 182. Accordingly, when the printing and spacing cut-out lever 194 is permitted to operate upon the selection of a function, not only will the arm 195 thereon act to block the movement 40 of link 161 and prevent the printing operation, but also, link 198 will be actuated rightwardly (as viewed in Fig. 6) to rock bell crank lever 199 clockwise to effect the withdrawal of pawl 182 from rack 181. Thus, when lever 194 operates in 45 a normal manner to perform the spacing operation, its action will be negated by the prior withdrawal of pawl 182 from the rack 181.

50 When a carriage return code signal is received to initiate the carriage return operation, the code bars 107 are set permutably in response thereto, thereby effecting the selection of the particular selector member 114 that is provided with depending arm 192, and that is also provided with a projection 200 which acts upon an arm 203 (Figs. 6 and 7) of a member 204 pivotally mounted on pins or trunnions 205 and 206. Member 204 is also provided with vertically extending arms 207 and 208 which engage pawls 188 and 182 respectively. Therefore, when the 55 carriage return selector member 114 is actuated by its spring 170, member 204 is rocked inwardly (away from the reader as viewed in Figs. 6 and 7) by the action of projection 200 upon arm 203 to effect the withdrawal of both pawls 188 and 182 from the rack 181 whereupon the platen carriage 176 is free to respond to the pull of the carriage return spring enclosed in the housing 101. Pawls 182 and 188 are held withdrawn from the rack 181 for the duration of the carriage return cycle, to insure the full return of carriage 176, by a latch 265 (Fig. 6) pivoted at 60 266 to the printer frame 41. Latch 265 is adapted, through the action of spring 267, to engage arm 207 of member 204, until it is disengaged by 65 70 75

the impingement of a pin (not shown), carried on the bottom side of platen carriage 176, upon the end 268 of latch 265. To absorb the blow caused by the rapid return movement of the platen carriage 176 in response to the action of the carriage return spring, a dashpot 209 is provided, a striker screw (not shown) being carried on the carriage 176 to strike the upper end of the dashpot operating lever 210 (Fig. 5) pivotally mounted at 211 on the printing frame 47, the lower end of which is pivotally articulated to a plunger associated with the dashpot 209 in the usual manner.

The line feed operation is controlled in a manner similar to the carriage return operation, by a particular selector member 114 which is selected upon the receipt of a line feed code signal. The line feed selector member 114 has a depending arm 212 to the lower end of which is pivoted one end of a link 213 (Figs. 1, 2, and 7) the other end of which is pivoted to an arm 214 (Figs. 1, 6, and 7) pivotally carried at the extremity of an arm 215 of the plural arm lever 184. Thus, when the line feed selector member 114 is selected, it is permitted to rotate clockwise thereby drawing the link 213 leftwardly (Figs. 1 and 6) to bring the free end of arm 214 into the path of depending arm 216 of a line feed lever 217 pivoted at 218 to the printer frame 47. Then, when the plural arm lever 184 is actuated in a clockwise direction by the spacing cam 35, arm 214 is urged forwardly as viewed in Fig. 6, or leftwardly as viewed in Fig. 3, to rotate the line feed lever 217 clockwise, which movement is effective, through a line feed pawl 219 carried on the end of lever 217, to rotate the line feed ratchet 221 a single angular step. As shown in Fig. 4, the line feed ratchet 221 is fixed to one end of a shaft 222, to the other end of which is fixed a gear 223 which meshes with a long pinion 224 so that the gear 223 has slidable meshing engagement therewith. In this manner, gear 223 is operatively connected with pinion 224 regardless of the character spacing position of the platen carriage 176. Therefore, when the ratchet 221 is rotated one angular step, this rotation is imparted through shaft 222 and gear 223 to the pinion 224, and thence through idler gear 225 to a gear 226 fixedly associated to the platen 172. Simultaneously, with the performance of the line feed function, the depending arm 212 also acts upon bail 193 to effect the suppression of the printing and spacing operations in the manner previously described.

The shift and unshift mechanisms are controlled by the particular selector members 114 having depending arms 227 and 228, respectively (Figs. 1 and 2). Pivotally connected to the depending arms 227 and 228 are links 229 and 231, respectively. Link 229 is pivoted to a latch member 232, and link 231 is pivoted to a latch member 233, which latch members are pivoted by common pivot 234 (Fig. 2) to the end of an arm 235 of the plural arm lever 184 (Figs. 1, 2, 5, and 6). Each time that the plural arm lever 184 is rocked by its cam 35, latches 232 and 233 are reciprocated frontwardly and rearwardly of the apparatus (or leftwardly and rightwardly, respectively, as view in Fig. 5). Latches 232 and 233 terminate in their free ends with laterally disposed positions, which under certain predetermined conditions engage the ends of arms 236 and 237, respectively. Arms 236 and 237 are pivoted at 238 and 239, respectively, to a shift

control lever 241 pivoted at 242 to the printer frame 47. Lever 241 is provided with a vertical extension, carrying at its upper end a stud 243 which fits into a groove 244 in the periphery of a sleeve 245 slidably mounted on the shaft 54. 5 Integral with sleeve 245 is the interponent 142 previously described, which is disposed between the two arms 141 and 143. Thus, when the shaft 54 rotates, the arm 141 of disc 139 fixed to shaft 54 imparts rotation not only through arm 10 142 to the sleeve 245, but also through interponent 142 and arm 143 to the cylinder 125. Arms 141 and 143 are normally biased attrahently by a common spring 140 (Figs. 3 and 6), and when the arms 141 and 143 assume the position closest 15 to each other, the relationship between the stop arms 100 and 122 and the type wheel 126 is such as to print upper case characters. However, when the sleeve 245 is shifted leftwardly, as viewed in Fig. 5, or forwardly, as viewed in Figs. 20 1 and 6, in a manner presently to be described, the arm 142 will act upon the inclined cam surfaces 247 and 248 (Fig. 6) on arms 141 and 143, respectively, to spread said arms 141 and 143 apart against the action of the common spring 25 140, thereby changing the angular relationship between the stop arms 100 and 122 on the cylinder 125 and the characters on type wheel 126 one character position to thereafter print the characters in the lower case position. The angular relationship between type wheel 126 and cylinder 125 is thus alterable because the type wheel is constrained to move with shaft 54 (to which disc 139 is also fixed) and cylinder 125 is freely mounted on said shaft. Therefore, it is manifest that through the medium of arm 142 and cam surfaces 247 and 248, the arms 141 and 143 may be spread apart to change said angular relationship, and upon retraction of arm 142 and the concurrent action of spring 140, the original relationship will be restored. 35

To effect the shifting and unshifting operations, one or the other of the arms 228 or 227, respectively, is actuated upon the selection of its associated selector member 114 in response to the shift or unshift code combinations, respectively. Upon the receipt of an unshift code combination, the particular selector bar 114 having the depending arm 228 will be actuated in a clockwise direction which, through link 231, will 45 rotate latch 233 clockwise, as viewed in Fig. 1, to bring its laterally disposed end into cooperative relation with the end of lever arm 237, whereafter upon the succeeding rocking movement of plural arm lever 184 imparted to it by 50 cam 35, the latch 233 will be actuated rearwardly and in so doing will pick up the lever arm 237, which will thereby also be actuated rearwardly to impart counterclockwise rotation (as viewed in Figs. 1 and 5) to the shift control lever 241. 55 This movement of lever 241 will cause, through stud 243, the sleeve 245 to be shifted leftwardly whereby the interponent 142 will act upon the cam surfaces 247 and 248 to spread the arms 141 and 143, respectively, thus changing the angular relationship between the stop arms 100 and 122 and the characters on type wheel 126 to print thereafter unshift or lower case characters, until a shift code combination is subsequently received. 65

When the shift code combination is received, the selector member 114 provided with the depending arm 227 is, upon selection, rocked clockwise to actuate the link 229 leftwardly to rotate arm 232 clockwise to bring its laterally disposed 70 75

end into cooperative relation with arm 236 whereafter, upon the ensuing rocking movement of plural arm lever 184, the arm 232 will be reciprocated; and upon the rearward movement in its reciprocating cycle, arm 232 will pick up the lever arm 236 to impart therethrough clockwise rotation to shift control lever 241, which through stud 243 will shift the sleeve 245 rightwardly to retract interponent 142 from the cam surfaces 247 and 248, whereupon spring 140 will again draw the arms 141 and 143 together, thus bringing the stop arms 100 and 122 and the characters on the type wheel 126 into that relation whereby shift or upper case characters will thereafter be printed. Simultaneously with the performance of the shift and unshift functions, the depending arms 228 and 227, respectively, also act upon bail 193 to effect the suppression of the printing and spacing operations as described hereinbefore. The position of the shift mechanism as shown in the drawings is such as to effect the printing of upper case characters.

The type wheel employed in the apparatus according to the present invention is shown in Fig. 8, and, as previously mentioned, comprises a flat circular disc having a series of radial slots 167 therein thus providing a plurality of radiating reeds 168 carrying, adjacent their circumferential ends, type faces 252. The lower case characters are designated by line 253, and the upper case characters are designated by line 254. It is thus noted that upper case and lower case characters are arranged alternately. However, for the purpose of the present disclosure, the angular distance between successive lower case characters is deemed to be one step, and correspondingly the angular distance between upper case characters is also deemed to be one step. Therefore, the distance between adjacent lower case and upper case characters is referred to as one-half step; that is, when the angular relationship between the characters on the type wheel and the stop arms 100 and 122 is such as to cause the printing of lower case characters, each shoulder on the ends of the stop arms 100 and 122 is effective with its associated selector member 113 or 114, as the case may be, to position a lower case character into printing position. Then, when it is desired to print upper case characters, the relationship between stop arms 100 and 122 and the selector members 113 and 114 is not changed, but the type wheel is shifted angularly, by the aforescribed shift mechanism, in relation to the stop arms so that when the shoulders on the stop arms coact with the selector members 113 and 114, an upper case character will be presented to the printing position.

While the total number of permutations obtainable with five code bars is thirty-two, and with the shift and unshift possibilities, this total number is doubled; namely, to sixty-four, the type wheel 126 would normally be provided with sixty-four angular positions which, in the present arrangement of characters, would leave eight more blank spaces than are shown in Fig. 8, to allow for the performance of functions. However, with the apparatus according to the present invention, provision is made for suppressing the printing and spacing operations when functions are performed, thus making it possible to eliminate eight of the blank spaces, thus permitting the type wheel to be divided into eight less divisions, having thereby fifty-six equal divisions instead of sixty-four, thus strengthening considerably the type wheel by making the reeds of

greater width. It is seen that by the elimination of eight blank spaces, the teeth on the star wheel 153 have been distributed to provide an arrangement (as indicated in Fig. 8) whereby on one side of the type wheel the teeth are arranged to span eight characters (as at 127) for each of four tooth-spaces on the star wheel 153, while on the other side of the type wheel the teeth are spaced to span six characters (as at 220) for each of four tooth-spaces on the star wheel, two blank spaces having been eliminated for each of the latter four tooth-spaces.

With the spacing of the teeth on star wheel 153 as indicated at 127, the stop arms 122 are arranged with their shoulders 230 and 124 spaced at regular angular intervals. However, by eliminating blank positions and thus reducing the number of character positions on the type wheel, it is possible to alter the position of certain ones of the shoulders 124 by making the shoulders 124 of two successive arms 122 and 100 coincident. The shoulders 230, then, of the arms 100 are thus advanced two angular spaces, to assume the angular position that would otherwise be assumed by its associated shoulder 124. In other words, the two arms 122 embraced in space 302 (Fig. 8) comprise four stop positions and include three of the aforementioned full steps; while the two arms 100 and 122 embraced in the space 137 comprise three stop positions and include two full steps. The teeth or points on star wheel 153 are so spaced as to stop the cylinder 125 in one of eight angular positions, wherein a pair of stop arms as 100 and 122 (or 122 and 122) associated with each pair of abutment members 113 and 114 are both in front of the ends 119 to assure that said abutment members, when selected, are presented into the path of the stop arms in proper sequence; that is, so that the forward or leading shoulder in each oncoming pair of stop arms is the first shoulder of the pair of arms to cooperate with the pair of abutment members in the event that the pair of abutment members is selectively operated simultaneously. There being eight groups of shoulders 124 and 230, there are eight positions of entry for ends 119, and the star wheel 153 is provided with eight points to cooperate with an arm 154 controlled by the transfer bail 148.

A further feature of the invention consists in providing a taut wire paper knife associated with the platen 172 as shown in Figs. 3, 4, and 10. As illustrated in Figs. 3 and 4, a backing plate 255 is mounted in platen carriage 176 above the platen 172, and positioned in front of plate 255 is a wire 256 which is provided with means for rendering it taut for paper carrying purposes. As shown in Fig. 10, wire 256 is folded back at its ends and is anchored in adjustable screws 257 and 258 carried in end plates 259 and 261, respectively of the platen carriage 176. The desired tautness of the wire 256 is established by turning the set screws 257 and 258 sufficiently, and lock nuts 262 and 263 are provided to maintain the tautness. The utility of a taut wire paper knife is emphasized by the fact that it does not interfere with the lines of printing due to the fact that it is of sufficient narrowness to be readily confined between the lines of printing.

General operation

A complete description of the cycle of operations involved in the printing of a character and also in the operation of a function will be 75

described. For example, it will be assumed that a character is to be printed, following which a function, such as "Shift" is to be performed.

As the signal impulses representing the character are applied to the selector magnet 83, the selector cam barrel 51 is released for operation in the manner fully described hereinbefore, and the selector fingers 94 are successively positioned in accordance with the received impulses. About 5 the time that the last of the impulses of the character code signal has been received, the clutch throwout lever 44 is tripped by operation of the lever 152 by the cam 190 of the cam drum 51 and the clutch 38 becomes engaged, whereby 10 rotation is imparted to the cams 35, 36, and 37. Almost immediately after the cams begin to rotate, the cam 36 operates its follower 136 (Fig. 6) which in turn, through lever 144, operates transfer bail 148, whereby the character code combination, in accordance with the setting of the selector fingers 94, is permitted to be transferred to the code bars 107. As the operation 20 of the transfer bail 148 causes the particular drop bar 113 which had been selected previously to be lifted out of the notches (and the detent 111 to be lifted out of the notches 112) the code bars 107 are shifted to present a new alignment of notches, whereafter upon the return of the transfer bail 148 to its former position another one 25 of the drop bars 113 will follow into the new alignment of notches.

Incidentally, while the transfer bail 148 was thus operated to raise the drop bars out of engagement with the code bars 107, thereupon lifting ends 119 out of abutting relation with the stop arms 100 and 122, the cylinder 125 was prevented from spinning by the presentation of end 154 of lever 155 into the path of the oncoming tooth of star wheel 153. Then, when the transfer bail 148 is returned to its clockwise position, end 154 is withdrawn from engagement with star wheel 153 to permit the rotation of cylinder 125 until one of the shoulders 230 or 124 of stop arms 100 or 122 abuts the end 119 of the newly selected 30 drop bar 113 or 114. Immediately after the type wheel 126 has been stopped under the control of cylinder 125, the printing cam 37 acts upon follower roller 158 to rotate lever 159 clockwise (Fig. 6) which permits the printing spring 165 to actuate the printing arm 162 clockwise (Fig. 3).

As previously mentioned, type wheel 126 is so spaced from the platen 172 as to provide visible printing. Therefore, the first portion of the clockwise movement of printing arm 162 is utilized (through hook 169 and head 171) to bring the type wheel 126 within printing range of the platen, whereafter the remainder of the operative stroke of the printing lever 162 is employed in effecting, through end 166, the printing 50 operation.

In proper timed relation with the printing operation, and preferably immediately thereafter, the character spacing of the platen is performed through the instrumentality of cam 35, which 55 through its follower roller causes lever 185 to be rotated clockwise (Fig. 6), whereupon spacing pawl 182 is actuated leftwardly, to move, through spacing rack 181, the platen carriage 176 leftwardly one character space.

Assuming that the next signal received is a shift code combination, the selector magnet 83 will respond to the impulses thereof to initiate the rotation of the cam barrel 51 and to control the setting of the selector fingers 94, in the manner previously described. At a timed instant 70

during the rotation of cam barrel 51, the cam 190 thereon will, through bail 45, effect the disengagement of clutch arm 44 and the consequent initiation of rotation of clutch 38. Upon the 5 operation of transfer bail 148 through the instrumentality of transfer cam 36 the setting of the code bars 107 in accordance with the shift code combination is permitted. When the transfer bail is returned to its normal position, the particular drop bar 114 having the depending 10 arm 227 is selected (that is, permitted to fall into an alignment of notches) and under the action of its spring 170 is permitted to rotate in a clockwise direction. Link 229 is thereupon actuated in a leftwardly direction to bring arm 232 15 into operative relation with arm 236 so that when the plural arm lever 184 (Fig. 6) is actuated in a clockwise manner by cam 35, latch member 232 will be reciprocated rightwardly, as viewed 20 in Fig. 5, and will engage arm 236 and impart thereto similar motion, causing the shift control lever 241 to be rocked in a clockwise direction which, through pin 243 (Fig. 1), will urge sleeve 245 to the right, permitting spring 140 to move arms 141 and 143 closer to each other. In this manner, the type wheel is permitted to move one-half step in the normal direction of movement of the cylinder 125 to condition upper case characters for printing.

On the other hand, in response to an unshift 30 code combination, that particular drop bar 114 having depending arm 228 will be selected whereby link 231 will be actuated leftwardly to bring latch member 233 into operative engagement with arm 237, so that upon the subsequent reciprocation of arm 233, lever 237 will be engaged and 35 shift control lever 241 will be rocked counterclockwise causing, through pin 243, sleeve 245 to be moved leftwardly, whereby arm 142 will 40 coact with cam surfaces 247 and 248 to spread arms 141 and 143 apart, against the action of spring 140, sufficiently to change the angular relationship between stop arms 122 and type wheel 126 one-half step, thereby conditioning the lower 45 case characters for printing.

Modification

In Fig. 11 is shown a modified form of selector mechanism wherein the stop arms are provided with forked ends, each tine or prong having two 50 steps or shoulders, and the drop bars are shiftable collectively at their abutment ends to cooperate with one or the other series of tines. Having reference to Fig. 11, the code bars 271 and 272 and the comb bar 273 (which is not provided 55 with code notches) are shiftable in code manner similar to the series of code bars 107 (Fig. 2) of the principal form of the invention, through the instrumentality of the T-levers 105 and associated members 94, 99, etc., of the selector mechanism 60 shown in Fig. 4. The code bars 271 and 272 and the comb bar 273, besides being pivotally articulated through notches 290 to T-levers analogous to T-levers 105, are slidably mounted on studs 275, are adapted to be set permutably in accordance with the received code 65 combinations of impulses by the selector mechanism described in connection with the preferred embodiment, and are retained in their set positions by the coaction of a spring actuated 70 detent member (not shown in Fig. 11, but analogous to detent member 111 shown in Fig. 4) with detent notches 271.

Cooperating with the code bars 271 and 272, and comb bar 273 is a plurality of selector drop bars 75

or abutment members 278. In the arrangement shown, there are eight members 278, which are not only mounted pivotally on shaft 279, but are, at the same time, swivelly movable thereon. The 5 ends 279 of arms 280 of the selector members 278 provide abutments for a series of stop arms 281 helically arranged around and affixed to a cylinder 282. Each stop arm 281 is provided with a forked end having two tines or prongs 283 and 10 284, and each tine terminates in a pair of stepped shoulders 285 and 286, one or the other of which impinges against a selected member 278, as will presently appear. Each of the arms 280 has a vertically extending projection 287 which cooperates with the comb bar 273.

The three code bars 272, when operated permutably, effect the selection of one of the drop bars 278. The bottom or comb bar 273, when shifted in response to one impulse of the received 20 code combinations, acts, due to its articulation through projections 287 to drop bars 278, to swivel the drop bars 278 on shaft 279 and thus shift collectively the ends 279 of arms 280 to one or the other series of tines 283 or 284, as 25 indicated in Fig. 11 by the solid line and dotted line positions. The top code bar 271, like code bar 120 of the principal embodiment, has its wards or projections only about one-half as high as the wards of the code bars 272, and for the 30 same purpose; namely, of determining with which shoulder 285 or 286 the end 279 of the selected drop bar 278 will abut. Summing up, code bars 272 determine which drop bar 278 will be selected or operated, comb bar 273 determines which of the pair of tines the selected 35 drop bar will cooperate with, and the top code bar 271 determines which shoulder 285 or 286 shall abut the end 279 of the selected drop bar.

The shoulders 285 and 286 are angularly arranged in a manner similar to shoulders 124 and 230, shown in Fig. 8. The cylinder 282 also has affixed thereto a star wheel 289, similar to the arrangement shown in connection with the principal embodiment of the invention, which star 45 wheel has cooperating therewith an anti-spin lever 291 (similar to member 154) associated with the transfer bail 288 (similar to transfer bail 148 of the preferred form of the invention).

The operation of the selector mechanism in 50 accordance with Fig. 11 is similar in many respects to the selector mechanism shown in the principal form of the invention in that the signal impulses representing the character are applied to the selector magnet 83 (Fig. 4), and the selector cam barrel 51 is released for operation to effect, through the cooperation of selector lever 79 and selector members 94, the selective 55 position of T-levers similar to T-levers 105. These T-levers are articulated to the code bars 271 and 272 of the comb bar 273 in a manner similar to that shown between T-levers 105 and code bars 107 in Fig. 4. In timed relation with the rotation of the selector cam barrel 51, the transfer bail 288 is operated (in a manner similar to transfer bail 148) to permit the 60 transference of the selection from the T-levers to the code and comb bars. As pointed out in connection with the preferred form of the invention, while the transfer bail 288 is thus operated 65 to raise the drop bars 278 out of engagement with the code bars 271 and 272 (the comb bar 273 not being provided with code notches), thereupon lifting end 279 out of abutting relation with the stop arms 281, the cylinder 282 is prevented 70 from spinning by the moving of lever 291 into any one of a plurality of character positions, a

the path of the oncoming tooth of the star wheel 289. Then, when the transfer bail 288 is returned to its clockwise position, lever 291 is withdrawn from engagement with the star wheel 289 to permit the rotation of cylinder 282 until one of the shoulders 285 or 286 of the stop arms 281 abuts the end 279 of the newly selected drop bar 278. After the type wheel has been stopped under the control of cylinder 282, the printing operation is effected in a manner similar to that described in the principal embodiment.

The invention herein described may be embodied in other specific forms without departing from the spirit or essential characteristics thereof. The present disclosure is therefore to be considered in all respects as illustrative and not restrictive, the scope of the invention being indicated by the appended claims rather than by the foregoing description, and all changes which come within the meaning and range of equivalency of the claims therefore intended to be embraced therein.

What is claimed is:

1. In a printing telegraph receiver, a rotatable type wheel provided with a plurality of characters, a member having a series of arms less in number than the number of characters on said type wheel for controlling the rotation thereof, stop means cooperable with said arms for controlling said member, and a permutation code selector mechanism for controlling said stop means.

2. In a selector, a rotatable shaft, arms having a plurality of abutting surfaces positioned on said shaft, and a permutation code selector mechanism cooperable with said surfaces to determine the stop position of said shaft.

3. In a printing telegraph receiver, a start-stop type wheel, a member having a helical series of arms, each arm provided with a plurality of abutting surfaces, for controlling the rotation of said type wheel, a stop element individual to each arm and cooperable with said abutting surfaces, a permutation code selector mechanism for controlling said stop elements, and therethrough the position of said type wheel, and a printing mechanism effective thereafter to print from said type wheel.

4. In a selector, a rotatable shaft arrestable in any one of a plurality of character positions, a cylinder carried by said shaft having projections thereon less in number than the available number of character positions, and abutment members corresponding in number to the number of said projections cooperable with said projections for determining the stop position of said shaft.

5. In a selector, a rotatable shaft arrestable in any one of a plurality of character positions, a cylinder carried by said shaft having projections thereon less in number than the number of character stop positions, mechanism for controlling the rotation of said cylinder, and a permutation code selector mechanism for controlling said mechanism to determine the stop position of said cylinder and shaft.

6. In a printing telegraph receiver, a type wheel, a member for controlling the rotation thereof, arms having a plurality of abutting surfaces arranged around said member, and a permutation code selector mechanism cooperable with said surfaces to determine the stop position of said member.

7. In a printing telegraph receiver, a type wheel, a rotatable shaft therefor arrestable in any one of a plurality of character positions, a

cylinder carried by said shaft having projections thereon less in number than the available number of character stopping positions, and abutment members corresponding in number to the 5 number of said projections cooperable with said projections for determining the stop position of said shaft.

8. In a printing telegraph receiver, a type wheel, a member for controlling the rotation 10 thereof, arms having a plurality of abutting surfaces arranged around said member, a permutation code selector mechanism comprising selectable abutment members cooperable with said surfaces to determine the stop position of said 15 member, and means to alter the operative relationship between said arms and said abutment members.

9. In a recorder, a rotatable shaft, arms having a plurality of abutting surfaces arranged 20 around said shaft, a permutation code selector mechanism comprising selectable abutment members cooperable with said surfaces to determine the stop position of said shaft, and means to alter the operative relationship 25 between said arms and said abutment members.

10. In a printing telegraph receiver, a shaft constantly tending to rotate, arms arranged around said shaft, a permutation code selector mechanism comprising selectable abutment 30 members cooperable with said arms to determine the stop position of said shaft, an intercepting member, and solely mechanical means to render said abutment members and said intercepting member alternately engageable with said arms to 35 prevent the spinning of said shaft during the period of reselection of said abutment members.

11. In a printing telegraph receiver, a shaft constantly tending to rotate, arms arranged around said shaft, a permutation code selector 40 mechanism comprising selectable abutment members cooperable with said arms to determine the stop position of said shaft, means operable on said abutment members to enable the reselection thereof, a star wheel fixed to said shaft, and means controlled by said means and 45 cooperable with said star wheel to prevent the spinning of said shaft during the period of reselection of said abutment members.

12. In a selector, a rotatable shaft, arms arranged around said shaft, a permutation code 50 selector mechanism comprising selectable abutment members cooperable with said arms to determine the stop position of said shaft, means to facilitate the reselection of said abutment members, and anti-spin means controlled by said 55 means and effective during the period of reselection to control said shaft.

13. In a printing telegraph receiver, a type wheel, a member for controlling the rotation 60 thereof, arms arranged around said member, a permutation code selector mechanism comprising elements cooperable with said arms to determine the stop position of said member, means acting on said elements periodically, and anti- 65 spin means acted upon by said means alternately with respect to said elements and effective during the period of reselection of said elements to control said member.

14. In a selector, a rotatable shaft arrestable 70 in any one of a plurality of character positions, a cylinder carried by said shaft having projections thereon, a permutation mechanism comprising elements cooperable with said projections to determine the stop position of said cylinder, means acting on said elements periodically, 75

and anti-spin means acted upon by said means alternately with respect to said elements and effective during the period of reselection of said elements to control said cylinder.

15. In a selector, a plurality of code bars, means controlled by signaling impulses for positioning said code bars, a plurality of selectable members, means for determining the selection of certain of said selectable members solely through the positioning of certain of said code bars, and means whereby other of said selectable members are conditioned for selective operation independently of the positioning of said certain code bars. 5 10

16. In a selector, a rotatable shaft arrestable in any one of a plurality of character positions, a cylinder carried by said shaft having projections thereon less in number than the available number of character stopping positions, abutment members corresponding in number to the 15 number of said projections, a plurality of code bars, and means controlled by signaling impulses for positioning said code bars to effect the selective operation of said abutment members for cooperation with said projections for determining the stop position of said shaft. 20 25

17. In a selector, a rotatable shaft, arms having a plurality of abutting surfaces positioned on said shaft, a permutation code selector mechanism comprising a plurality of code bars, means controlled by signaling impulses for positioning said code bars, a plurality of selectable members selected upon the positioning of certain of said code bars independently of the position of the remaining code bars to determine certain stop 30 positions of said shaft, and other selectable instrumentalities conditioned upon the positioning of said remaining code bars to determine other stop positions of said shaft. 35

18. In a printing telegraph receiver, a rotatable type wheel provided with a plurality of characters, a member having a series of arms each arranged with a plurality of shoulders for controlling the rotation of said type wheel, stop means cooperable with said shoulders for controlling said member, a plurality of code bars, and means 40 controlled by signaling impulses for positioning said code bars to determine the cooperative relationship between said stop means and said shoulders. 45

19. In a printing telegraph receiver, a rotatable type wheel, a member having a helical series of arms each arranged with a plurality of shoulders for controlling the rotation thereof, a stop element individual to each arm and cooperable with said shoulders, a plurality of code bars, and means 50 controlled by signaling impulses for positioning said code bars to determine the cooperative relationship between said stop elements and said shoulders. 55

20. In a printing telegraph receiver, a type 60 wheel, a member for controlling the rotation thereof, arms having a plurality of abutting surfaces arranged around said member, a plurality of code bars, means controlled by signaling impulses for positioning said code bars, a plurality 65 of abutment members, means for determining the selection of certain of said abutment members solely through the positioning of certain of said code bars to cooperate with said surfaces in a certain manner, and means whereby other of said 70 abutment members are conditioned for selective operation independently of the positioning of said certain code bars to cooperate with said surfaces in a different manner. 75

21. In a recorder, a rotatable shaft, arms hav-

- ing forked ends arranged around said shaft, a selector mechanism comprising selectable abutment members cooperable with the forked ends to determine the stop position of said shaft, and means to swivel said abutment members into operative relationship with corresponding series of ends of said arms. 5
22. In a printing telegraph receiver, a shaft constantly tending to rotate, forked arms having a plurality of tines arranged around said shaft, each tine being provided with a plurality of stepped abutting surfaces, a selector mechanism comprising selectable abutment members cooperable with said surfaces to determine the stop position of said member, means to change the operative relationship between said abutment members and said surfaces, and means to change the operative relationship between said abutments and said tines. 10
23. In a printing telegraph receiver, a type wheel, a rotatable shaft therefor arrestable in any one of a plurality of character positions, a cylinder carried by said shaft provided with projections less in number than the available number of character stopping positions, and abutment members less in number than the number of said projections cooperable with said projections for determining the stop position of said shaft. 15
24. In a printing telegraph receiver, a type wheel, a rotatable shaft therefor arrestable in any one of a plurality of character positions, a cylinder carried by said shaft provided with projections less in number than the available number of character stopping positions, abutment members less in number than the number of said projections cooperable with said projections for determining the stop position of said shaft, means for controlling the operative relationship between said abutments and said projections in a certain manner, and means for controlling the operative relationship between said abutments and said projections in a different manner. 20
25. In a printing telegraph receiver, a type wheel, a member for controlling the rotation thereof, arms having a plurality of abutting surfaces arranged around said member, selecting means comprising a plurality of selectable abutment members cooperable with said surfaces to determine the stop position of said member, means for controlling the operative relationship between said abutment members and said surfaces in a certain manner, and means for controlling the operative relationship between said abutments and said surfaces in a different manner. 25
26. In a printing telegraph receiver, a shaft, a type wheel on said shaft, means also on said shaft for determining its stop position for printing from said type wheel, a plurality of code bars mounted parallel and in juxtaposition to said shaft, means responsive to signaling impulses for setting said code bars, and means intermediate said code bars and the means on said shaft and selective through the setting thereof and cooperating with the means on said shaft for stopping said shaft and said type wheel in the desired printing position. 30
27. In a selector, a plurality of code bars, a plurality of selectable elements less in number than the letters of the alphabet, means responsive to signaling impulses for setting said code bars to determine the selection of said elements, means for precluding the operation of the selected element for a predetermined period of a cycle of operation, a plurality of type elements, and means operated through the selection and operation of a selectable element for determining the type element to be operated. 35
28. In a recorder, a rotatable shaft, arms having forked ends arranged on the periphery of said shaft, a selector mechanism comprising selectable members cooperable with the forked ends of said arms to determine the stop position of said shaft, and means to swivel said members into operative relationship with corresponding series of ends of said arms. 40

HOWARD L. KRUM.
